FIG-1

FIG-2

FIG- 3

FIG- 4

FIGURE 1 is a top plan view of an automobile service building showing our new design;

FIGURE 2 is a front elevation view;

FIGURE 3 is a side elevation view; and

FIGURE 4 is an enlarged side elevational view of the spire of the building, shown in FIGURE 3, partially broken away for convenience of illustration only.

The side opposite to that shown in FIGURE 3 is substantially identical to that shown in FIGURE 3.

We claim:

The ornamental design for an automobile service building, as shown and described.
